BRAKE MECHANISM

Louis H. Doyle, Clinton, Iowa, assignor of two-thirds to H. R. Russell, Long Beach, Calif.

Application December 14, 1931, Serial No. 580,928

1 Claim. (Cl. 188—232)

This invention which relates to brake mechanism for railway cars is concerned more particularly with a brake beam assembly having certain features of advantage.

5 It is the usual practice to provide a car with a horizontal compression member which is located a few inches below the center line of the car wheels. The brake heads attached to the ends of the compression member are shaped to fit the 10 wheel contour and the compression member end, and are therefore adapted to fit only diagonally opposite wheels of the same truck, being incapable of use when turned upside down.

15 The present construction is advantageous in that the brake heads may be used in any one of the several positions on each car truck. The brake shoes are likewise reversible on the brake heads. These and other advantages will more specifically appear as the description proceeds.

20 As an exemplification of my invention, reference is made to the accompanying drawing in which—

Figure 1 is a perspective view of a compression member having assembled therewith the strut, 25 brake heads, and compression rod;

Fig. 2 is an enlarged side elevation of the strut member as viewed on line 2 of Fig. 1;

Fig. 3 is a sectional view of the heel of the strut taken as indicated by line 3 of Fig. 2;

30 Fig. 4 is a sectional view of the strut taken as indicated by line 4 of Fig. 2; and

Fig. 5 is a sectional view of the strut taken as indicated by line 5 of Fig. 2.

Referring to Fig. 1, I have shown a brake beam 35 C adapted to be supported by hangers in a well known manner. Each beam may comprise a tension member 12, brake heads 13 secured to each end thereof by a tension rod 14, and a strut 15 interposed between the compression member and 40 compression rod.

The tubular strut 15 is of substantially uniform diameter throughout the major portion of its length and provided at its outer end with a wide cross groove 45, to receive the tension rod, and 45 with forwardly extending projections 46 so spaced and shaped as to permit reversed position of the strut. A slot 47 is formed in the strut, at an angle of about 40° with the vertical, for the reception of a brake lever 48, pivoted on a bolt 49 50 in a bore 50 extending transversely through the strut.

The inner end of the tubular strut 15 is reduced, as shown in Figs. 2 and 3, to provide a heel 55 having two sets of parallel flange engaging surfaces and a vertical flange end engaging shoulder adjacent each surface; the two sets of parallel 5 surfaces intersecting at diametrically opposite points with the circumference of the tubular strut.

The heel 55 of the strut is diamond-shaped so that when it is turned from one position in the compression member to another, it is axially 10 moved through about 80°. Thus the slot 47 will always be close to 40° one side or the other from the vertical. The strut is retained in position by a key 56 extending through slots 57 and 58 in the compression member and heel of the strut, 15 respectively, and bent over to lock the same in place.

The parts constituting the brake beam C are assembled together, as shown in Fig. 1, with the tension rods extended through suitable openings 20 in the brake heads. Nuts 32 which are in threaded connection with the tension rod ends abut the outside of the heads to secure all the parts together. Preferably, the nuts are provided with 25 saw-tooth notches 33 adapted to engage teeth 34 formed on the brake head to prevent loosening of the nuts.

The present construction fulfills all the requirements of the American Railway Association and 30 may be installed on all present rolling stock without altering the hangers or changing the position of the brake levers.

I claim:

In a brake beam assembly, a compression member having a pair of spaced flanges providing a channel therebetween, and a strut for the compression member comprising a tubular bar having a reduced end extension providing a heel adapted to fit within the channel of said compression member and seat adjacent the opposed flanges thereof, said heel being substantially diamond shape in cross section providing two sets of oppositely disposed parallel flange engaging surfaces, which surfaces intersect at diametrically 45 opposite points within the circumference of said tubular strut providing shoulders adjacent each flange engaging surface adapted to abut the ends of said flanges.

LOUIS H. DOYLE. 50
